UNITED STATES PATENT OFFICE.

PHILIPPE FRIEDERICK, OF SALINA, KANSAS.

BUTTONHOLE-SCISSORS.

1,080,145.

Specification of Letters Patent.

Patented Dec. 2, 1913.

Application filed April 7, 1913. Serial No. 759,569.

To all whom it may concern:

Be it known that I, PHILIPPE FRIEDERICK, a citizen of the United States, residing at Salina, in the county of Saline and State 5 of Kansas, have invented a new and useful Buttonhole-Scissors, of which the following is a specification.

The present invention appertains to button hole scissors, and particularly to an improved adjusting device therefor to limit the closing movements of the cutters or blades so that button holes of predetermined sizes may be cut.

It is the object of the present invention 15 to provide a novel and improved adjustable stop carried by the shank of one blade to contact with the other shank, whereby the closing movements of the blades may be adjusted to a nicety without the liability of 20 variance in the size of the button hole cut after the stop has been once set.

It is also the object of the present invention to provide a device of the character indicated, which shall be comparatively 25 simple, durable, compact and inexpensive in construction, as well as efficient, convenient and serviceable in its use, the same being capable of simple and easy adjustment.

With the foregoing general objects out- 30 lined and with other objects in view, which will be apparent as the nature of the invention is better understood, the invention resides in the combination and arrangement of parts and in the details of construction hereinafter described and claimed, it being understood that changes in the precise embodiment of the invention herein disclosed, can be made within the scope of 35 what is claimed without departing from the spirit of the invention.

The preferred embodiment of the invention has been illustrated in the accompanying drawing, wherein:—

Figure 1 is a side elevation of a pair of button hole scissors embodying the improved stop. Fig. 2 is an enlarged fragmental section of the shank of one blade and illustrating the improved stop applied thereto, parts of the stop device being shown in full 45 and parts being shown in section and the relative parts being shown in position for permitting the adjustment of the stop. Fig. 50 3 is a perspective view of the actuating member. Fig. 4 is a perspective view of the

stop proper. Fig. 5 is a bottom or inner 55 end view of the plug.

In carrying out the invention, reference being had in detail to the drawing, the shanks 2 of the blades or cutters 1, are provided with the respective coöperating enlargements 3 and 4, which stand transversely adjoining the pivotal point of the blades. The enlargement 3 is provided with a threaded bore 5 extending longitudinally therethrough, the bore being disposed transversely or laterally relative to the respective shank 2, and at its outer end, the bore 5 is provided with a threaded counter bore or socket 6 forming a shoulder or seat 7. The bore proper 5 is relatively 65 long, while the counter bore or socket 6 is relatively short, although the particular proportions are of no great moment.

The stop proper has been designated by the numeral 8, the same being threaded 75 through the bore 5, and having a slot or kerf 9 extending from its inner end to a point directly short of its outer end, the slot 9 extending completely between the opposite sides of the stop 8. The inner end of 80 the slot 9, however, is contracted by a pair of lips 10 inturned from the inner ends of the respective leaves or sections of the stop 8. The stop 8 is preferably of a length 85 slightly longer than the bore 5 proper, it being noted that the inner end of the stop 8 is adapted to contact with the enlargement 4 of the respective shank 2.

A plug 11 is threaded into the counter bore or socket 6, and is provided with the inner recess 12. The plug 11 is further provided with an extension 13, projecting outwardly therefrom, and which is preferably square or otherwise fashioned for engagement with a suitable wrench for facilitating the engagement and detachment of the plug when necessary. The plug is also provided with a square or non-circular opening 14 extending from the recess 12 through the extension 13, it being understood that the recess 12 is circular.

The actuating member for the stop 8 embodies a flat tongue 15 taking into the slot 9 and having a knob 16 at its inner end working snugly between the sides or walls of the slot 9, while the tongue itself works snugly between the lips 10, so that when the tongue and stop are separated or moved apart suffi-

ciently, the knob 16 will engage the lips 10 and will thus prevent the stop and tongue from separating, unless the tongue is moved laterally out of engagement with the slot 9.

5 Thus, it will be noted that the tongue may be readily moved into and out of engagement with the stop 8, by inserting it or removing it laterally into or out of the slot 9, the tongue and stop, however, being prevented from separating longitudinally.

10 The tongue 15 is provided with a collar or circular enlargement 17 at its butt or outer end, which fits snugly within the recess 12 of the plug. A square or noncircular portion 18 projects outwardly from the collar or enlargement 7, while a stem or shank 19 projects outwardly from the portion 18, and has a head or thumb piece 20 secured to its outer end in any suitable manner, the 15 head or thumb piece 20 being spaced slightly from the square portion or boss 18. The stem or shank 19 passes through the non-circular opening 14 of the plug 11, the said opening being adapted to receive the non-circular portion 18 of the actuating member 20 so as to lock the actuating member against rotation. Thus, when the actuating member is pressed or slid inwardly by means of the head 20, the head is adapted to 25 seat against the extension of the plug, and the square portion 18 is simultaneously disengaged or withdrawn from the opening 14, so that the actuating member is free to rotate.

30 35 A coiled wire compression spring 21 is disposed with the counter bore or socket 6, and is seated between the shoulder 7 and the collar 17 of the actuating member so that the spring normally tends to press the actuating member outwardly so that the square portion engages the square opening of the plug to thereby lock the actuating member against rotation. However, the actuating member is yieldingly held in normal or non- 40 rotatable position, so that it may be conveniently forced inwardly by the operator, in order that the actuating member may be rotated by hand.

45 It will be apparent that the foregoing parts may be readily manufactured, and assembled with or applied to the scissors. Thus, in applying the relative parts to the scissors, the stop 8 is preferably first threaded into the bore 5 and only partially so, and then the spring 21 is preferably slipped into the socket 6 around the stop 8. The actuating member, with the plug 11 carried thereby between the collar 17 and head, is then positioned, the inner end of the tongue 15 50 being inserted laterally into the slot 9 as will be apparent. The plug 11 is then threaded tightly into the socket 6, so that it will be held against accidental or casual displacement. The device will then be in 55 condition for operation, the spring 21 en-

gaging the collar 17, and yieldingly sliding the actuating member into locked position.

In use, as above noted, the actuating member will be normally pressed outwardly so that the portion 18 thereof engages with in the opening 14 of the plug to thereby lock the actuating member against rotation, it being noted that the tongue 15 is flat and fits snugly within the slot 9 of the stop to prevent the stop from rotating unless the actuating member is rotated. Thus, the stop and actuating member are adapted to slide longitudinally relative to each other, but are constrained from rotation with respect to each other. To adjust the stop 8, it is merely necessary to press the head inwardly, or against the plug, which will withdraw the portion 18 of the actuating member from the opening 14 of the plug, and as a consequence, the actuating member is free to rotate. Then, by rotating the actuating member, the stop 8 will be rotated, and may thus be screwed inwardly or outwardly to the position desired, the stop 8 being made to travel longitudinally while the actuating member is merely rotated. After the stop has been positioned as desired, the head 20 is released, so that the spring 21 will again press the collar 17 outwardly to lock the squared portion or boss 18 within the opening 14 of the plug. The enlargement 4 of the respective shank is preferably provided with a socket or recess 22 in its inner end into which the inner end of the stop 8 is engaged or seated so as to limit the closing movements of the blade or cutters 1, it being noted that by adjusting the stop 8, various sizes of button holes may be cut. There will be no liability of the stop to loosen, which would result in the variance in the sizes of the button holes cut, it being noted that the stop 8 is normally locked against rotation. It is to be observed, also, that when the stop 8 is projected inwardly sufficiently, so that the inner end reaches the inner end of the bore 5, the lips 10 will engage the knob 16 of the tongue 15 so as to prevent any further movement of the stop, which will prevent the stop from becoming accidentally detached, which might otherwise result from carelessness on the part of the operator.

55 It is to be understood that the improved stop is not only applicable to button hole scissors but may be applied to other devices wherein two members or parts are movable to and from each other, as will be understood.

Having thus described the invention, what is claimed as new is:—

1. In combination with a pair of members movable toward each other, a stop in threaded engagement with one member to contact with the other, an actuating member rotatably carried by the aforesaid mem- 125
130

- ber, having limited sliding movements and slidably engaging the stop to turn therewith, and means for locking the actuating member against rotation when slid to a predetermined position.
2. In combination with a pair of members movable toward each other, a stop in threaded engagement with one member to contact with the other, and having a longitudinal slot extending from its outer end, an actuating member rotatably carried by the aforesaid member having limited sliding movements, the actuating member embodying a tongue working within the said slot, and means for locking the actuating member against rotation when slid to a predetermined position.
3. In combination with a pair of members movable toward each other, a stop in threaded engagement with one member to contact with the other, and having a longitudinal kerf extending from its outer end to a point short of its inner end, an actuating member rotatably carried by the first mentioned member and having limited sliding movements, the actuating member including a flat tongue engaging within the said kerf and having a knob at its inner end fitting snugly within the kerf, the actuating member having inturned lips at its outer end between which the tongue is snugly disposed, and means for locking the actuating member against rotation when slid to a predetermined position.
4. In combination with a pair of members movable toward each other, one member having a transverse bore, a stop threaded through the bore and projectable from the inner end of the bore, a member engaged to the aforesaid shank at the outer end of the bore, and an actuating member rotatably carried by the said member and having limited sliding movements relative thereto, the actuating member having a portion in slidably engagement with the stop, and the said member and actuating member having portions adapted to interlock when the actuating member is slid to a predetermined position.
5. In combination with a pair of members movable toward each other, one member having a transverse bore, a stop threaded through the bore to contact with the other member, a plug engaged within the outer end of the bore, an actuating member rotatably carried by the plug and having limited sliding movements, the actuating member being slidably engaged with the stop to turn therewith, and the plug and actuating member having coöperating non-circular portions adapted to interlock when the actuating member is slid to a predetermined position.
6. In combination with a pair of members movable toward each other, one member having a transverse bore, a stop threaded through the bore to contact with the other member, a plug engaged within the outer end of the bore, and an actuating member passing through the plug and slidably connected to the stop to turn therewith, the actuating member having a non-circular portion, the plug having a non-circular opening to receive the said non-circular portion when the actuating member is slid outwardly, and the actuating member being provided with a head seatable against the plug when the actuating member is slid inwardly.
7. In combination with a pair of members movable toward each other, one member having a transverse bore, and a counter bore at the other end of said bore, a stop threaded through the aforesaid bore, a plug engaged within the counter bore, and having a non-circular opening, an actuating member having a tongue slidably engaging a stop to turn therewith, the tongue having a non-circular portion at its butt end to be engaged within the said opening and having a stem passing through the said opening, a head carried by the outer end of the said stem to seat against the plug, and a coiled wire spring seated within the counter bore to coöperate with the actuating member to yieldingly force the same outwardly to engage the non-circular portion with the said opening of the plug.
8. In combination with a pair of members movable toward each other, one member having a transverse bore, and a counter bore at the outer end of the said bore, a stop threaded through the aforesaid bore, to contact with the other member, a plug engaged within the counter bore, the plug having an inner recess and a non-circular opening extending from the recess to the outer end, an actuating member embodying a tongue slidably engaging the stop to turn therewith and having a collar at the butt end of the tongue fitting snugly within the recess of the plug, the collar having a non-circular portion projecting outwardly therefrom and the said portion having a stem projecting through the said opening in the plug, a head secured to the outer end of the stem and adapted to seat against the plug, and a coiled wire spring seated within the counter bore and engaging the said collar to press the non-circular portion into engagement with the said opening in the plug.
- In testimony that I claim the foregoing as my own, I have hereto affixed my signature in the presence of two witnesses.

PHILIPPE FRIEDERICK.
